UNITED STATES PATENT OFFICE.

GEORGE HARRIS, OF SAN FRANCISCO, CALIFORNIA.

DRUM.

SPECIFICATION forming part of Letters Patent No. 795,034, dated July 18, 1905.

Application filed November 5, 1904. Serial No. 231,512.

To all whom it may concern:

Be it known that I, GEORGE HARRIS, a subject of the King of Great Britain, residing in the city and county of San Francisco and State 5 of California, have invented new and useful Improvements in Drums, of which the following is a specification.

This invention relates to improvements made in the construction of drums and other 10 similar musical instruments that comprise a head of prepared skin stretched over a hoop or a cylindrical frame of wood or metal.

The improvements embrace a novel means or device for stretching and also for varying 15 the tension of the skin of both heads of a double drum by a single tension-screw; also, a novel fixing means for stretching the head in place; also, a novel construction and combination of body and rim, all as hereinafter more fully 20 described, and pointed out in the claims at the end of this specification.

The following description explains at length 25 the manner in which I proceed to construct, apply, and carry out my said invention, the accompanying drawings being referred to by figures and letters.

Figure 1 represents in elevation a double drum with my improvements applied thereto. Fig. 2 is a perspective view of a segment or 30 portion of the body and rim of the drum, showing the shape and relative position of the parts as they appear in section. Fig. 3 is a vertical sectional view of the step-bearings for the foot of the tension-screw. Fig. 4 is 35 a front view of one of the semicircular saddle-blocks that are fixed on the rim of the drum to carry the tension-cord. Fig. 5 is an edge view of the same block. Fig. 6 is a vertical cross-section showing in detail the rim, the 40 ring to which the edge of the skin is attached, and a portion of the shell or body of the drum. Fig. 7 is an elevation of the parts, on an enlarged scale, showing in detail a construction of thrust-bearing for the screw- 45 shaft.

In describing the construction and application of the present improvements the parts of the drum are designated and referred to herein as the body *a*, the rim *b*, the hoop *d*, 50 the head *e*, and the ring *f*. Following the

general construction of these instruments the body *a* is sometimes made of metal and sometimes of wood. The hoop *d* is usually made of wood. The rim *b* is a circular and continuous ring of metal with a horizontal flange 2 55 extending outwardly at right angles from the perpendicular outer face of the rim to seat on the end of the body *a*, and a similar flange *3* on the opposite side extending inward at right angles to the upright member of the rim furnishes a support for the grooved ring *f*. The parts of this rim and their position with reference to the other parts will be understood from Fig. 2 of the drawings.

The skin *e* of the head being attached to a 65 flat ring *g* is clamped between the outside flange *2* and the hoop *d* and is firmly held all around the edge by drawing and holding the hoop to a close seat upon the ring *g* by means of the lacing *4* and lacing-hooks *5* on the 70 hoops at both ends of the drum. For better security in holding the skin under tension it is wrapped around the ring *g* from the inside and brought over the front edge, so as to lie upon the top face of the ring, as seen in Fig. 75 2. This brings the skin between the ring *g* and the hoop *d*, as well as between the ring *g* and the flange *2*, thereby affording a double hold on the skin at all points around the circle. The edge of the skin may also be glued 80 to the ring for greater security. This means of attaching the skin to the body of the drum contributes to the production of an even and uniform tension of the head, for the reason that it holds the skin firmly at all points 85 around the circumference. In connection with this clamping means the device for stretching and giving the required tension to the head is constructed and applied with a view to act on both heads at the same time, 90 and by the simple movement of a tension-screw it produces the required degree of tension on the skins of both heads. The construction and operation of this tension device will be readily understood from Figs. 1 and 95 2 of the drawings.

A ring *f*, having a deep groove in its outer edge extending around the circumference, lies on the inner flange *3*, by which it is supported behind or within the rim *b* in such position 100

that the top face of the ring stands above the top edge of the rim and the bottom of the groove in the ring is about flush with the top edge of the rim. Supported in this position 5 on the inside of the rim *b* and above the plane of the outer flange *2* the grooved ring raises the surface of the skin above the rim, so as to turn the marginal portion of the skin all around the circumference perpendicularly 10 downward over the groove, when the edge of the skin is clamped between the hoop and the flange *2*, and by drawing into the groove a cord *h* the head is stretched and maintained under the required degree of tension. One 15 end of the cord *h* is brought to the outside through a slit *6* in the hoop *d* and made fast to a block *7*, and from that point the cord being laid around the circumference between the skin *e* and the inner face of the hoop *d* it 20 is carried through a slit *8* in the hoop to the outside, as seen in Fig. 1 on the left side of the figure, at the upper hoop. From the point *8* where it passes out from the upper hoop the cord *h* is brought down to the lower hoop 25 and is laid around the rim of the lower head by being carried in at the slit *10* and out at the slit *12* after passing entirely around the circumference of the head. The end of the cord is finally made fast to a block *7*, fixed 30 on the body above the lower hoop. A quadrant-shaped block *m* with a grooved rim is fixed on the body of the drum in line with the slit *6*, and similar grooved blocks *m*¹ *m*² *m*³ are fixed on the body in the required position 35 in line with each slit to change the direction of the cord and carry it in a regular curve at right angles, or thereabout. The function of these blocks is to reduce the strain on the cord *h* at these points. It will be obvious 40 that ordinary sheaves or small grooved wheels could be employed instead of these quadrant-shaped blocks for the same purpose. The tension device located on the outside of the drum between these two points where the 45 cord leads out through the hoops is composed of a screw-threaded rod or shaft *s*, mounted for rotation in stationary supports *13* *14*, and a traveling nut *t*, working on the screw-threaded portion of the rod and having a curved 50 saddle-piece *15* *16* with a grooved top edge, in which is laid the cord *h*. In order to apply the pulling strain of the saddle-piece upon the cords in the proper direction, it is necessary to bring the cord over the top of the 55 saddle-piece from below on both sides of the line of the screw-threaded rod, and for that purpose a third block *p* is employed. This block is fastened to the shell or body on the side of the threaded rod *s* opposite to that 60 where the grooved block *m*² is located, and it is formed or provided with a semicircular rim, so as to turn the cord upward and bring it over the traveling nut in nearly a vertical direction from below.

65 While it is rotatable in its bearings on the

side of the body, the screw-rod is held against moving longitudinally by a collar *18*, situated below the socket-piece *13*, and it is provided on the upper end with a square head *17* to take a key for turning it. The lower end of 70 the rod is fitted to a bearing in a bracket *14*, secured to the shell *a*. On being rotated the screw-rod *s* acts on the traveling nut to set it up or down on the rod, with the effect to throw greater or less strain on the cord *h*, and thereby increase or reduce the tension on 75 both heads at the same time by a simple turn of the screw-rod.

In connection with the tension device when applied to a large drum, such as a bass-drum, 80 where the end thrust of the screw-rod in the bracket *14* is obviously much greater than in the case of a side drum, I provide a thrust-bearing of novel character, in which the upward pressure of a spring-bearing operates 85 to counteract the end pressure of the screw-rod. The construction of this yielding bearing is clearly shown in Fig. 7 of the drawings. On the bracket *14* beneath the bearing *20* a box *21* furnishes a guide for a movable block *22* or nut *22* with a screw-threaded socket, through which a screw-thread *23* on the lower portion of the screw-rod *s* is fitted to work. The thread *23* on that portion of the rod has a contrary pitch to the threaded portion on 95 which the saddle-piece *t* travels, one being a left-hand thread and the other a right-hand thread. The effect of this construction is to cause the lower block *22* to move on the rod in the opposite direction to the part *t*. Between the bearing-block *22* and the bottom of the box *21* a stiff coiled spring *25* is interposed, so as to resist the movement of the block downward in the box and by its reaction under compression to counteract the 100 downward thrust of the screw-rod with increasing force or pressure in proportion as the thrust becomes greater under the movement of the screw-rod. The upward pressure of the coiled spring against the block *21* 105 at such time will reduce the frictional resistance between the collar *26* on the screw-rod and the face of the fixed bearing *20*.

Having thus described my invention, what I claim as new, and desire to secure by Letters 115 Patent, is—

1. In a drum or like musical instrument, a body, a separable rim having an outer flange adapted to seat on the edge of the body and an inwardly-extending flange, a hoop, a ring interposed between the hoop and the outer flange of the rim, and to which the skin is attached all around the circumference of the head, a lacing adapted to hold the hoop to a seat on the said ring, a second ring having a 120 groove extending into its outer edge circumferentially thereof, said grooved ring being interposed between the skin and the inner flange of the rim, a cord in line with said groove around the circumference of the ring 125 130

and means for drawing up and maintaining tension on said cord.

2. In a drum or like musical instrument, a cylindrical body, a rim seated on the edge and separable from the body and having an inwardly - extending flange, a hoop, a ring clamped between the hoop and the rim, a skin having its marginal edge wrapped around the ring a lacing adapted to hold the hoop in place on the ring, a ring of smaller diameter than the hoop and supported within it beneath the skin, said ring having a groove in the outer edge, a cord in line with said groove and extending circumferentially around the same against the skin, one end of the said cord being attached to a fixed point on the body and means for drawing up and maintaining tension of the cord.

3. In a drum or like musical instrument, the combination with a body, a skin head, and means for clamping the marginal edge of the skin all around the circumference; of a ring beneath the skin of the head having a grooved outer edge over which the skin is stretched, a cord extending around the circumference of the head in line with the grooved edge of the ring, and means for drawing up and maintaining tension on the cord, comprising a screw-threaded rotatable shaft, a traveling nut thereon, a saddle-piece carried by the nut over which the cord is laid, and grooved blocks for changing the angular direction of the strain on said cord.

4. In a device for drawing up and maintaining tension on the skin of a drumhead or other like musical instrument the combination with a ring supported beneath the skin

and having a grooved outer edge and means for clamping the marginal edge of the skin all around the circumference outside the 40 grooved ring; of a cord extending around the circumference of said ring in line with the groove and exteriorly of the skin, and means for drawing up and maintaining tension on the cord, comprising a grooved stationary 45 guide, a screw-threaded rotatable shaft, a nut traveling on said shaft, and a saddle-piece on the nut over which the cord is carried from the stationary guide.

5. In a device for tightening a drumhead, 50 the combination with a ring supported beneath the skin of the head and having a groove in the outer edge and means for clamping the marginal edge of the skin outside the ring; of means for drawing up and tightening the skin, 55 comprising a screw-shaft having reversely-threaded portions one above the other, a nut provided with a saddle-piece fitted to travel on one thread, a nut fitted to the other thread a fixed box for the nut in which it is adapted 60 to move as the shaft is rotated a coiled spring between the nut and the end of the box and a tightening-cord extending around the grooved ring on the outside of the skin and in line with the groove and stationary cord-guides on the 65 body of the drum arranged to carry the cord over the saddle-piece of the traveling nut.

In testimony whereof I have hereunto set my name to this specification in the presence of two subscribing witnesses.

GEORGE HARRIS.
